UNITED STATES PATENT OFFICE.

EDUARD VON SALIS, OF WINTERTHUR, SWITZERLAND, ASSIGNOR TO BUSCH-SULZER BROS.-DIESEL ENGINE COMPANY, OF ST. LOUIS, MISSOURI, A CORPORATION OF MISSOURI.

FUEL-INJECTION MEANS AND METHOD.

Application filed May 3, 1926, Serial No. 106,272, and in Switzerland July 1, 1925.

The invention relates to injection type internal combustion engines having accumulators in their fuel lines and its object is to improve the general efficiency of this type of engine as below made apparent. To this end, the invention consists broadly in controlling the pressure exerted by the accumulator, under variations of the volume of the injection fuel charge, so that such pressure is high enough for the minimum fuel charge and not much higher for the maximum charge. In this way the fuel pumps are called upon to do little or no more work when under full load or overload than when the engine is idling and with a corresponding saving of energy as well as economy of structure, the injection velocity being adequately high for both conditions. The control referred to can be accomplished manually or automatically, and when accomplished automatically, by a variety of mechanical embodiments not greatly differing in general structure from existing accumulators and hence easily accommodated to existing power plants.

In the drawing Fig. 1 diagrammatically represents an example of one automatic embodiment of the invention.

Fig. 2, another, and

Fig. 3 illustrates the apparatus in which the method can be manually performed.

Referring to Fig. 1: The fuel is delivered by a variable delivery fuel pump 1 diagrammatically shown but understood to be driven by the engine and controlled by hand or by governor in the usual way. The fuel is forced by the pump, through pipe 2, to the accumulator cylinder 3 and thence by pipe 4 to the injector or spray valve 5, which is of a known type in which the pressure of the fuel opens the injection passage as will be understood from the diagram.

The accumulator consists essentially of a spring-pressed plunger 6 as usual but the spring acts on a cross-head 7 which moves in its housing 8 transversely or at an angle to the plunger axis, being connected to it by means of a thrust-link 9. The effect of this relative arrangement of plunger and spring is that on a small fuel charge, delivered by the pump, with a correspondingly small displacement of the accumulator plunger, the link has a less favorable angle for compressing the spring, and on a larger fuel charge and great-

er displacement of plunger 6, it has a more favorable angle. Thereby the pressure exerted by the spring on the accumulator plunger is greater than proportional to the volume of the charge at low load (charge) and less than proportional to the volume at high load (charge) than it would be if the spring acted directly on the plunger, as in the usual arrangement. In other words, the accumulator pressure increases at a less rate than the volume of fuel charge increases. Desirably, the accumulator pressure increase could be zero, at least above a certain minimum pressure adequate for producing proper injection velocity for the smallest fuel charge. It will be obvious to those skilled in this art that the rate of pressure increase can be controlled variously.

The variation of such pressure can also be accomplished in steps or stages, if desired, and within this invention, as illustrated in Fig. 2, wherein small fuel charges displace the accumulator plunger 10 by corresponding amounts up to the point where the plunger uncovers port 11. For such small displacements, the accumulator pressure and the fuel volume will vary together and uniformly, according to the characteristics of the spring employed. When the port 11 is uncovered the resilience of an auxiliary accumulator device diagrammatically represented by 11 is brought into play reducing the pressure on the fuel. This auxiliary device may be an air chamber or another accumulator spring as will be understood. In like manner, the rate of change of the accumulator pressure can be accomplished in more than two stages.

In Fig. 3, three or more accumulator devices, marked 13, 14 and 15 respectively, are connected in or to the fuel line and are intended to be successively opened to the line as by manipulation of the valves 16 and 17, according as the volume of the fuel charge is varied by manipulation of the control handle on the variable delivery pump. For the smaller charges, only the accumulator 13 will be active; for medium charge the accumulators 13 and 14 will be active, and for full load charges, all three of them.

Having described the invention, the following is claimed:

1. In injection type engines the combination with the fuel pump and fuel injector, of a

plurality of resilient accumulator means, and means for bringing them successively into action.

2. The method of controlling the fuel supply of injection type engines having fuel accumulators, which consists in relieving the pressure-increasing resistance which the accumulator offers in response to increase in the volume of the fuel charge, whereby the accumulator pressure increases at a rate less than proportional to the rate of increase of the volume of the fuel charge.

3. The method of controlling the fuel supply of injection type engines having fuel accumulators, which consists in increasing the

effective volume of the accumulator, as the volume of the fuel charge increases, at a rate greater than is proportional to the rate of increase of charge volume.

4. In an injection type engine, the combination with a fuel pump and fuel injector device, of an accumulator, including resilient means exerting pressure on the fuel, and means for lessening the rate of increase of said pressure as the pressure rises in response to increased volume of the fuel charge. 20 25

In testimony whereof, I have signed this specification.

EDUARD von SALIS.
